UNITED STATES PATENT OFFICE

EMIL A. PETERSON, OF APPLETON, WISCONSIN, ASSIGNOR TO VALLEY IRON WORKS COMPANY, OF APPLETON, WISCONSIN, A CORPORATION OF WISCONSIN

JORDAN ENGINE

Application filed August 26, 1929. Serial No. 388,352.

This invention relates to Jordan engines and has particular reference to improved means for mounting the knives of the plug of such an engine.

5 The objects of the invention are to provide means for facilitating mounting, removal or replacement of the knives on a Jordan plug; to provide means which will effectively maintain the knives in proper operative position, while at the same time being such that the mounting or replacement of knives on the plug may be accomplished with considerably less labor and in considerably less time than has heretofore been required; to provide 10 means for mounting the knives which will permit the provision of deeper spaces between the knives than has heretofore been practicable; and, in general, it is the object of my invention to provide an improved Jordan 15 plug.

Other objects and advantages of the invention will be understood by reference to the following specification and accompanying two sheets of drawings, in which I have illustrated a part of a Jordan engine equipped 20 with a plug embodying a selected form of my invention.

In the drawings:

Figure 1 is a fragmentary longitudinal sectional view of a part of a Jordan engine including a part of the plug.

Figure 2 is a side elevation of a part of my improved plug structure.

35 Figures 3 and 4 are fragmentary sections of the plug on the lines 3—3 and 4—4, respectively, of Figure 1.

Figure 5 is an illustration of a part of the structure shown in Figure 1, but on an enlarged scale, and showing the structure in greater detail.

Figures 6 and 7 are side elevations of the long and short knives which are mounted on the plug.

45 Figure 8 is a side elevation of a device

which is used for supporting the knives in operative position.

Referring now to the drawings, I have indicated the outer shell of a Jordan engine at 10 and the plug which fits inside of the shell 50 at 11. The plug 11 is carried by an axle or shaft 12 which is journaled in suitable bearings which are provided in any approved manner, the plug body 11 and shaft 12 being splined or otherwise locked together so that 55 the plug body 11 may be rotated within the shell through the agency of the shaft 12. A head member 13 is bolted to the small end of the shell 10, and is provided with an inlet opening 14 and a head member 15 is bolted to 60 the large end of the shell 10 and is provided with an outlet 16.

Knives such as indicated at 17 are mounted in the shell 10 in any approved manner, it being understood that there is a plurality of 65 knives 17 projecting inwardly from the shell in circumferentially spaced relation. The plug body 11 is also provided with knives such as indicated at 18 and 19, the plug knives 18 and 19 cooperating with the knives 70 17 of the shell when the plug is rotated to reduce paper stock passed through the engine to a suitable degree of fineness.

As above indicated, my present invention has particular reference to improved means 75 for mounting the knives 18 and 19 on the plug body 11. My improved mounting means includes the provision of a plurality (three in the present instance) of annular boss-like formations 20, 21 and 22 on the surface of the plug intermediate its ends. As shown, the annular bosses are spaced longitudinally of the plug, and these bosses are provided with recesses or slots such as shown at 23, which extend crosswise of the bosses 80 (longitudinally of the plug), the slots being cut deep enough so that the bottoms thereof are in effect continuations of the surface of the plug body. It will of course be understood that the annular bosses are provided with a 85 90

plurality of recesses or slots 23 spaced circumferentially around the slot, the slots being adapted to receive and position the knives 18 and 19 in their proper operative relationship. In accordance with well known practice, the larger end of the plug, which is of frusto-conical shape, is provided with a plurality of short knives 19, which are located intermediate the full length knives 18. Accordingly, the bosses 21 and 22 are provided with slots to receive the short knives in addition to the slots for receiving the long knives.

For anchoring the knives on the plug against radial outward displacement, I provide means for interlocking the knives and plug body, this means including annular members such as 24, which are seated on shouldered portions 25 of the plug, the shoulders being conveniently formed as a part of the bosses 20, 21 and 22 which are cut away to provide the seats as desired. The annular members 24 are permanently mounted on the plug by being shrunk and pinned on the shouldered portions 25 by means of pins, as shown at 26, so that the annular member cannot be rotated relative to the plug. The annular members 24 are provided with laterally projecting flange portions 27 which extend over the adjacent ends of the grooves 23, as clearly shown in Figures 1 and 5. The knives 18 and 19 are provided with hook-like formations in their lower edges by recessing the knives as shown at 28, these recesses being undercut as shown at 29, so as to form the projecting portions 30 which are adapted to fit under the projecting flange portions 27 of the annular members 24. The recesses 28 are of sufficient width to permit the knives to be slipped over the annular members 24, and thereafter moved endwise to cause the projecting portions 30 and 27 to interlock.

The inner ends of the short knives 19 are provided with outwardly, endwise projecting portions 31, which are adapted to fit under the projecting portion 27 of the middle annular member 24, so that the inner ends of these short knives are effectively locked against radial outward displacement.

For supporting or maintaining the knives 18 and 19 in operative position, that is to say, in the desired circumferentially spaced relation, filler elements are provided which fit between said knives. These filler elements are divided into upper and lower portions, the lower portion being formed of a pair of wedge strips 32, 32 and a wedge 33. The wedge strips 32, 32 are preferably made of suitable wood and are provided with adjacent inclined faces 34, between which the wedge 33 is adapted to be driven so as to spread the strips 32 into engagement with the adjacent faces of the knives. As shown in Figures 3 and 4, the knives are of such cross section that the spaces therebetween are wider adjacent the bottoms of the knives

than at the top thereof, reference being had to the portions of the adjacent faces with which the wedging devices and filler elements co-operate. The wedge strips 32 obviously may be inserted from the outside of the plug, i. e., by movement of the wedge strips in a direction transverse to the length of the knives. When the wedge strips 32, 32, are positioned as desired, the wedge 33 may be driven in from the outside of the plug, thereby to separate the said wedge strips so as to form a tight-fitting 3-piece filler element which serves to effectively hold the knives in operative position. The wedge strips 32 and wedges 33 are in lengths which fit between the adjacent annular members 24 and between the annular members 24 and the adjacent ends of the plug. Accordingly the wedge strips are provided with recessed end portions as indicated at 35, the narrowed end portions fitting over the respective annular bosses 20, 21 and 22. As clearly shown in Figure 1, the plug body 11 is also provided with annular bosses 36 and 37 at its opposite ends, these bosses being also slotted to receive the knives in the manner in which the bosses 20, 21 and 22 are slotted.

For locking the wedging devices 32, 32 and 33 in operative position, I provide locking strips 38 which fit in the spaces between the knives outside of the said wedging devices. The locking strips 38 are slightly wedge-shaped in cross section so that the width of the strip at its bottom face is wider than its width at its top face, whereby the strip must be inserted between the knives by being moved endwise from one end of the plug. Obviously, the wedge strips 38 when inserted in this manner cannot come out in a radial direction from the plug, because of the increased bottom width of the same as compared with the reduced width of the space at the upper or outer end thereof. Because of the arrangement of long and short knives, as clearly shown in Figure 2, the locking strips are divided transversely into inlet end strips 38^a and outlet end strips 38^b, the latter being considerably narrower than the strips 38^a so as to fit in the narrower spaces between the alternately arranged short and long knives. The knives 18 and their inlet end wedging devices and locking strips are first mounted on the plug, after which the knives 19 and their wedging devices and locking strips are assembled.

For holding the knives in place at their outer ends, I provide end members 39 and 40 which are removably mounted on the inlet and outlet ends, respectively, of the plug, the end member 39 is provided with an inwardly projecting, annular flange 41 which is adapted to fit over projecting end portions 42 of the long knives 18, and the end member 40 is provided with an annular flange part 42 projecting inwardly of the plug and adapted

to fit over end projections 43 and 44 of the long and short knives, respectively. The end member 39 is preferably arranged so that it acts as a stop for the locking strips, there-
5 by facilitating assembling thereof.

The end members 39 and 40 may be remov-
ably mounted on the plug in any suitable
manner, one means being by cap screws such
as shown at 45, and suitable means may be
10 provided for facilitating removal of these
end members when desired. One such means
may be to provide tapped openings through
the respective end members which are nor-
mally closed by means of a plug fitting such
15 tapped openings. The plugs may be removed
and replaced by cap screws or the like which
fit the tapped openings, whereby, when the
screws are turned in, into engagement with
the ends of the plug body, the respective end
20 members 39 and 40 will be jacked out of
place.

The wedge strips 32, 32 are preferably of
wood, such as oak or other suitable kind,
which when wet swells and accordingly tends
25 to exert an increased holding pressure on the
knives. In order to more securely hold the
knives in place against radial displacement,
I provide the knives with one or more open-
ings 46, into which the wedge strips 32 may
30 swell, as indicated at 47, to thereby form, in
effect, an interlocking connection between the
wedge strips and knives.

I am aware that changes may be made in
the above-described structure without de-
35 parting from the spirit of my invention, the
scope of which should be determined by re-
ference to the following claims, construing
the same as broadly as possible consistent
with the state of the art.

40 I claim as my invention:

1. In a plug for a Jordan engine, the com-
bination of a plug body, a plurality of knives
mounted on said body in circumferentially
45 spaced relation, means for maintaining said
knives in said spaced relation comprising
wedging devices insertable between adjacent
knives in a radial direction relative to the
plug from the outside thereof, and independ-
50 ent wedging means fitting between said
knives outside of said wedging devices for
locking the respective wedging devices in
operative position.

2. In a plug for a Jordan engine, the com-
bination of a plug body, a plurality of knives
55 mounted on the surface of said body in cir-
cumferentially spaced relation, said knives
being so shaped in cross section as to pro-
vide spaces between adjacent knives which
are wider at their bottoms than at their tops,
60 means for supporting said knives in said
spaced relation comprising wedging devices
insertable between the adjacent knives in a
radial direction relative to the plug from the
outside thereof, and means for locking said
65 wedging devices in operative position com-

prising locking bars having greater inside
width than outside width and fitting snugly
in the space between adjacent knives outside
of said wedging devices and insertable into
operative position by endwise movement be-
70 tween the knives.

3. In a plug for a Jordan engine, the com-
bination of a plug body, a plurality of knives
mounted on the surface of said body in cir-
cumferentially spaced relation, said knives
extending longitudinally of the plug, means
75 for supporting the knives in said spaced rela-
tion comprising wedging devices insertable
between adjacent knives in a radial direction
relative to the plug and knives from the out-
side of the plug, said wedging devices com-
80 prising a pair of wedge strips fitting between
adjacent knives and a wedge adapted to be
driven between the strips from the outside of
the plug to wedge the same into engagement
with said knives, and means for locking said
85 wedge in operative position.

4. In a plug for a Jordan engine, the com-
bination of a plug body, a plurality of knives
adapted to be mounted on the surface of said
body in circumferentially spaced relation,
said knives extending longitudinally of the
90 plug and being so shaped in cross section that
the spaces between the knives are wider at
their bottoms than at their tops, means for
supporting said knives in said spaced rela-
tion comprising wedging devices insertable
95 between adjacent knives in a radial direction
relative to the plug from the outside thereof,
said wedging devices comprising a pair of
wedge strips fitting between adjacent knives
and a wedge adapted to be driven between the
100 strips to wedge the same into engagement
with said knives, and means for locking said
wedge strips into operative position, com-
prising locking strips fitting between adja-
cent knives outside of said wedging devices,
said locking strip being shaped in cross sec-
105 tion to correspond to the cross-sectional shape
of the space occupied thereby and being
adapted to be driven into place.

5. In a plug for a Jordan engine, the com-
bination of a plug body, a plurality of knives
mounted on the surface of said body in cir-
cumferentially spaced relation, said knives
extending longitudinally of the plug, means
115 for interlocking said knives and plug body
so as to prevent radially outward displace-
ment of the knives from the plug, said inter-
locking means being adapted to be engaged
or disengaged by relative endwise movement
between said parts, means in the spaces be-
120 tween adjacent knives for supporting the
same in spaced relation, said means compris-
ing inner wedging devices adapted to be in-
serted in the spaces between said knives from
the outside of the plug and in a radial direc-
125 tion relative to the plug, and outer locking
strips adapted to be inserted into said space
130

over said wedging devices, said locking strips being insertable by endwise movement from one end of the plug.

6. In a plug for a Jordan engine, the combination of a plug body, an annular boss on the surface of said body intermediate its ends, said boss being provided with a plurality of circumferentially spaced slots extending longitudinally of the plug, the bottoms of 10 said slots being substantially coincident with the surface of the plug body, an annular member permanently mounted on said plug body, associated with said boss and provided with a flange extending laterally over portions 15 of said slots, a plurality of knives respectively seated in said slots and provided with recessed portions adapted to interlock with said laterally projecting flange so as to anchor the knives against radial outward 20 displacement from the plug body, and means fitting in the spaces between said knives for maintaining the same in operative position.

7. In a plug for a Jordan engine, the combination of a plug body, a plurality of knives 25 mounted on said body in circumferentially spaced relation, wedging devices extending longitudinally of said knives and fitting in the spaces therebetween for maintaining the same in operative position, said wedging devices being insertable from the outside of 30 the plug body in a radial direction relative to said plug body and knives, said knives being so shaped in cross section as to provide spaces therebetween outside of said wedging devices 35 which are wider at their bottoms than at their tops, and means fitting in said spaces for preventing radial outward displacement of said wedging devices.

8. In a plug for a Jordan engine, the combination of a plug body, a plurality of knives 40 extending longitudinally of said plug body and mounted thereon in circumferentially spaced relation, an annular, outwardly projecting member on said plug body intermediate its ends having interlocking engagement with said knives for preventing radial outward displacement thereof, end members 45 removably mounted on said plug body and having interlocking engagement with the adjacent ends of said knives for preventing radial outward displacement of the knives at 50 their ends, independent means on opposite sides of said annular member, in the spaces between said knives and between said annular member and end members for supporting said knives in operative position, said means being insertable from the outside of the plug 55 in a radial direction relative to the plug body and knives, and means for locking said wedging devices in operative position, comprising locking strips disposed in the spaces between 60 said knives, outside of said wedging devices, said knives and locking strips being arranged so that the locking strips are insertable in 65 said spaces or removable therefrom only by

relative endwise movement between the locking strips and knives.

9. In a plug for a Jordan engine, the combination of a plug body, a plurality of knives 70 mounted on the surface on said body in circumferentially spaced relation, said knives being so shaped in cross section as to provide spaces therebetween which are wider at their bottoms than at their tops, means fitting in said spaces for locking the knives in operative position, and means radially spaced from 75 said locking means for securing the latter in place.
